UNITED STATES PATENT OFFICE.

ADOLF DECHER, OF MUNICH, GERMANY.

ROTARY ENGINE.

SPECIFICATION forming part of Letters Patent No. 297,575, dated April 29, 1884.

Application filed October 11, 1883. (No model.) Patented in France August 31, 1883, No. 144,929.

To all whom it may concern:

Be it known that I, ADOLF DECHER, a citizen of the German Empire, residing at Munich, in the German Empire, have invented 5 certain new and useful Improvements in Rotary Engines, (for which I have obtained Letters Patent in France, No. 144,929, under date of August 31, 1883;) and I do hereby declare the following to be a full, clear, and exact description of the invention, such as will enable others skilled in the art to which it appertains to make and use the same, reference being had to the accompanying drawings, and to the letters of reference marked thereon, 15 which form a part of this specification.

The invention has for its object to simplify the construction and increase the efficiency of rotary engines, as hereinafter more fully described, and as shown in the accompanying 20 drawings, in which—

Figure 1 is a vertical transverse section; Fig. 2, a like horizontal section; and Fig. 3 is a section through the valve-box.

Like letters of reference indicate like parts 25 wherever such may occur in the above figures of drawings.

The engine is composed, essentially, of a cylinder, A, closed at both ends by heads A' A'', the former being constructed to form a 30 chamber or casing, a', that contains the valve h, the cover a of said chamber being provided with a stuffing-box, a''. The cylinder A is divided into two chambers, C C', by a partition, H; and a shaft, B, located centrally 35 in the cylinder A, stepped at one end in the head A'', passes through the partition H, the head A', valve-casing a', its cover a, and the stuffing-box a'', and carries at its opposite end a belt or other driving pulley or wheel. The 40 shaft B carries four wings or blades, D D' and D'' D', projecting therefrom radially, their outer faces or edges being in close contact with the cylinder-walls. These blades or wings D D' are arranged in pairs upon the shaft, one 45 pair, D, being located in the upper and the other, D', in the lower cylinder-chamber, and at right angles to each other, as plainly shown in Figs. 1 and 2, and their inclination is about ninety degrees. The cylinder-walls are provided with recesses for the reception of seg-

mental regulating or controlling wings or blades E, located on opposite sides of said cylinder, as shown in Fig. 2, and fit steam-tight to the cylinder-head A', and occupy about one hundred and eighty degrees of the 55 circle of the cylinder—that is to say, they are formed of segments having a radius of about ninety degrees. Each of these wings or blades coincides with a steam-port, b. The steam admitted through the ports b acts first upon 60 the wings or blades E, which cause the wings D and shaft B to rotate; then the steam acts directly upon a portion of the said wings D, and, after having performed its work, passes out of the cylinder through the exhaust-pipes 65 d. The alternate admission of steam to the two compartments, C C', is so regulated as to act during one-quarter of a revolution of the shaft only, and twice during each entire revolution. By means of this arrangement steam 70 is admitted to and exhausted from the cylinder at each quarter-revolution of the shaft B, and the function of the operative devices is completed reciprocally. The valve h is composed of two segments connected by arms with 75 a sleeve, h', secured to the shaft B, and rotates with it. The segments of the valve, having a radius of ninety degrees, occupy each one-fourth of the interior space of the valve box or casing a', and alternately open and close the 80 steam-ports b', through which the connecting-pipes g and the steam-ports b the steam passes into the chambers C C' during the operation of the regulating-wings E, the steam being cut off as soon as said wings cease to act. 85 It will be apparent that, instead of steam, any other suitable motive power may be employed to drive the engine—such, for instance, as a gas or liquid.

Having thus described my invention, what 90 I claim, and desire to secure by Letters Patent of the United States, is—

In a rotary engine, the combination of a working-cylinder divided into two chambers by a horizontal partition, each chamber having two abutment-valves, E E, and steam inlet and outlet ports b g, with a shaft, B, provided with two piston-wings, D, for each chamber, a rotary valve, h, rigidly connected with shaft B, and operating in a valve-chest formed 95 100

on one of the heads of the cylinder, and suitable connections between said valve, the source of steam-supply, and the cylinder-chambers, and connections to exhaust the spent steam from said chambers, said parts being constructed for co-operation substantially as described.

5 In testimony that I claim the foregoing I

have hereunto set my hand this 13th day of August, 1883.

ADOLF DECHER.
